UNITED STATES PATENT OFFICE

WILLIAM E. WINE, OF TOLEDO, OHIO

RAILWAY CAR

Application filed September 11, 1930. Serial No. 481,298.

My invention relates to railway cars and more particularly to cars of the hopper type.

Due to the fact that moisture, acids and the like, contained in lading shipped in hopper cars quickly settles into the hoppers the portions of the hopper sheets adjacent the lower ends, that is, the discharge ends of the hoppers rapidly deteriorate and thereby cause weakening of the entire hopper structure. A principal object of the invention is, therefore, to provide improved means for reinforcing the lower portions of the hoppers and for tying together the hoppers which are arranged in pairs.

15 A primary feature of the invention consists in providing a railway car having a pair of hoppers with a member for tying the hoppers together and for reinforcing their lower portions, said member comprising a beam rigidly secured to the undersides of the hoppers and a plurality of upwardly projecting legs secured to the sides thereof.

20 Another feature of the invention consists in providing a railway car having a pair of hoppers with a beam member extending beneath and rigidly secured to each of the hoppers, the beam member being integrally formed with a plurality of pairs of upwardly extending legs, the legs of each pair being rigidly secured to opposite sides of an adjacent hopper.

25 A further feature of the invention resides in providing a railway car having a pair of hoppers with a beam member extending transversely of the car and rigidly secured to the undersides of the hoppers, said beam being integrally formed with outwardly projecting flanges respectively adapted to coact with adjacent marginal flanges of the hopper doors to form a seal against the escape of fine lading.

30 A still further feature of the invention consists in providing a railway car having a hopper comprising a slope sheet and inner and outer side sheets with a reinforcing member formed with upwardly extending legs adapted to be rigidly secured in overlapping relation to portions of the side sheets of the hopper bordering the lading discharge opening of the latter.

A still further feature of the invention consists in providing the reinforcing member with an enlarged portion constituting a mounting for a door supporting mechanism.

35 Other and more specific features of the invention residing in advantageous forms, combinations and relations of parts will herein-after appear and be pointed out in the claims.

40 In the drawings illustrating a preferred embodiment of the invention:

Figure 1 is an end elevational view of portions of a pair of hoppers showing my invention applied thereto, the view being normal to the plane of the lading discharge opening of the hoppers.

45 Figure 2 is a sectional view taken on line 2—2, Figure 1.

50 Figure 3 is a fragmentary side elevational view of one of the hoppers adjacent its discharge end, the door supporting mechanism being shown in dotted lines.

55 Figure 4 is a sectional view taken on line 4—4, Figure 3, the view also showing in elevation the cover plate of the door supporting mechanism.

60 Figure 5 is a sectional view taken on line 5—5, Figure 3, the view also showing the cover plate of the door mechanism in section.

65 Figure 6 is a sectional view taken on line 6—6, Figure 3.

70 Figure 7 is an enlarged sectional view taken on line 7—7, Figure 1.

75 Figure 8 is an enlarged sectional view taken on line 8—8, Figure 1.

80 Referring more particularly to the drawings there is shown in Figure 1 portions of two hoppers of a railway car of the saw-tooth type which, as is well known, are arranged on opposite sides of the center sill (not shown) of the car and constitute a pair. The hoppers of each pair are similarly formed and each has a slope sheet 1 and inner and outer side sheets 2 and 3, respectively, the side sheets preferably terminating in inturned flanges 4 for attachment by rivets 5 to the underside of the associated slope sheet. Pivots associated with each of the 106

hoppers is a door 6 for closing the lading discharge opening thereof. These doors are preferably formed of sheet metal and each is provided with outwardly projecting inner and outer side marginal flanges 7 and 8 and a bottom marginal flange 9. The doors of each pair of hoppers are connected by a beam 10, commonly termed a spreader, so that they will swing as one. In the present embodiment of the invention the spreader is of substantially Z-shape having a web 11 disposed at right angles to the doors and inner and outer oppositely projecting flanges 12 and 13, the inner flange contacting with the outer face of the doors and being rigidly secured thereto by rivets 14.

As may be seen in the drawings the inner side sheet of each hopper is formed with an inwardly offset portion 15 to afford a seat for the door 6. This portion which is preferably integrally connected to the main body portion of the inner side sheet by an inclined portion 16 is formed with an outwardly projecting flange 17 adapted to operate with the adjacent marginal flange 7 of the door to act as a seal against the escape of fine lading. Overlappingly secured to the outer side sheet of each hopper is a reinforcing member 18 of substantially channel shape having outwardly projecting flanges or portions 19 and 20 and an intermediate connecting web 21. The portion 20 affords a seat for the adjacent outer side edge of the door and it preferably terminates in an outwardly projecting flange 22 for cooperating with the adjacent side marginal flange 8 of the door to form a seal therewith against the escape of fine lading. The flange 22 and portion 20 of the reinforcing member 18 preferably terminate adjacent the lower edge of the hopper while the flange 18 and web 21 are bent inwardly to underlie the slope sheet 1 for attachment thereto by the rivets 5.

The combined tie and reinforcing member for the pair of hoppers involves a beam 23 which extends continuously from one hopper to the other beneath their slope sheets. As may be seen from Figure 8 this beam is of substantially angular shape having flanges 24 and 25, respectively, the former constituting means by which the beam may be rigidly secured by rivets 26 to the slope sheets of the hoppers and the latter serving as stiffening means. If desired, the lower portion of the flange 25 may be enlarged as at 27 to form a bulb or the like to further rigidify the beam. Where it underlies the slope sheets of the hoppers the flange 24 is angularly offset to provide a door seat portion 28 and an outwardly projecting flange 29 for coacting with the lower marginal flange 9 of the door to prevent the escape of fine lading from the hopper.

Extending upwardly from the beam and formed integrally therewith are a plurality of pairs of legs, the legs of each pair being respectively designated by the reference numerals 30 and 31. The leg 30 is formed with a plurality of offset portions 32, 33 and 34, the portion 32 being secured by rivets 35 in overlapping relation to the inclined portion 16 of the inner side hopper sheet while the portions 33 and 34 are respectively disposed in overlapping relation to adjacent portions of the door seat 15 and the outwardly projecting flange 17. The legs 30 may advantageously be reinforced by triangularly shaped gussets or flanges 36 which are preferably disposed in the plane of and constitute continuations of the flange 25 of the beam. The legs 31 which extend upwardly from the outer ends of the beam 23 are provided with portions 37, 38 and 39 respectively arranged in overlapping relation to the web 21, door seat portion 20 and flange 22 of the channel shaped member 18. The portion 37 is preferably secured to the member 18 and the outer side sheet of the hopper by rivets 40 and 45.

The portions 33 and 38 of the legs 30 and 31 respectively constitute continuations of the portion 28 of the beam while the portions 34 and 39 respectively constitute continuations of the sealing flange 29. Furthermore, the stiffening flange 25 may continue upwardly as at 41 along the inner edge of the legs 31. The upper ends of the legs 31 are enlarged as at 42 to afford mountings for suitable mechanisms for maintaining the hopper doors in closed positions. Each of these mountings is formed with a plate-like portion 43 spaced outwardly from the adjacent side sheet of the hopper and disposed in the same plane as the portion 39 of the leg. Projecting inwardly from the plate portion 43 are a plurality of bosses provided with apertures 44 to receive rivets 45 for connecting the door supporting mechanism to the combined tie and reinforcing member. Each door mechanism preferably comprises a hook 46, a cam 47 and a cover plate 48, the latter being formed with a plurality of inwardly projecting bosses 49, 50 and 51. The bosses are apertured to receive the attaching rivets 45 and the one designated 49 affords a pivotal support for the hook 46 while the one designated 50 affords a pivotal support for the cam 47. The hook is designed to cooperate with an arm 52 rigidly secured to the door and to the adjacent end of the door spreader 10 and extends beyond the adjacent side edge of the door.

In order that the mountings for the door supporting mechanisms may effectively resist the forces transmitted to them incident to maintaining the doors in closed positions the plate portion 43 of each is formed with inwardly projecting marginal flanges 53 and 54.

an additional inwardly projecting flange 54 which connects the lowermost of the marginal flanges 53 and the uppermost apertured boss 44. The mounting is additionally reinforced by the upwardly projecting portion 41 of the stiffening flange.

From the foregoing it will be perceived that strong and rugged means is provided for reinforcing the lower portions of hoppers of railway cars and for rigidly tying the hoppers together.

I claim:

1. In a railway car, the combination with a pair of spaced hoppers, each of said hoppers being provided with a hingedly mounted door, of mechanisms for respectively maintaining said door in closed positions, each of said mechanisms involving a movably mounted locking member, a combined tie and reinforcing member for the hoppers comprising a beam extending beneath and rigidly secured to each of the hoppers adjacent their lower ends, said beam being integrally formed with upwardly extending legs rigidly secured to the sides of the hoppers, the movable locking members of said mechanisms being respectively mounted on said legs.
2. In a railway car, the combination with a pair of spaced hoppers, each of said hoppers comprising a slope sheet and inner and outer side sheets, of a combined tie and reinforcing member for the hoppers comprising a beam extending beneath and rigidly secured to the slope sheets of each of the hoppers, said beam being integrally formed with upwardly projecting legs adapted to be respectively secured in overlapping relation to the inner sheets of the hoppers.
3. In a railway car, the combination with a pair of spaced hoppers, each of said hoppers being provided with a hingedly mounted door and involving a slope sheet and inner and outer side sheets, of a combined tie and reinforcing member for the hoppers comprising a beam extending beneath and rigidly secured to the slope sheets of each of the hoppers, said beam being integrally formed adjacent its opposite ends with upwardly extending legs respectively secured in overlapping relation to the outer side sheets of the hoppers, and means movably mounted on each of said legs for cooperating with the adjacent hopper door to maintain the latter in closed position.
4. In a railway car, the combination with a pair of spaced hoppers, each of said hoppers comprising a slope sheet and inner and outer side sheets, of a combined tie and reinforcing member for the hoppers comprising a beam extending beneath and rigidly secured to the slope sheets of each of the hoppers, said beam being formed with two pairs of upwardly extending legs, the legs of each pair being respectively secured to the inner and outer side sheets of the adjacent hoppers.
5. In a railway car, the combination with a pair of spaced hoppers respectively having lading discharge openings, each of said hoppers being provided with a door for closing its discharge opening, of a member extending beneath and rigidly secured to said hoppers adjacent their discharge openings, said member being integrally formed with portions affording seats for the doors of the hoppers.
6. In a railway car, the combination with a pair of spaced hoppers respectively having lading discharge openings, each of said hoppers being provided with a door for closing its discharge opening, said doors being respectively formed with outwardly projecting marginal flanges, of a member extending beneath and rigidly secured to the hoppers for connecting the latter, said member being integrally formed with outwardly projecting flanges respectively adapted to overlap the marginal flanges adjacent the lower edges of the doors when the latter are in closed positions to prevent the escape of fine lading.
7. In a railway car, the combination with a pair of spaced hoppers, of a combined tie and reinforcing member for the hoppers comprising a beam extending beneath and rigidly secured to each of the hoppers, the portion of the beam intermediate the hoppers being of substantially angle shape and integrally formed with upwardly projecting legs rigidly secured to the inner sides of the hoppers, each of said legs being formed with a reinforcing flange.
8. In a railway car, the combination with a pair of spaced hoppers, of a combined tie and reinforcing member for the hoppers comprising a beam extending beneath and rigidly secured to each of the hoppers, the outer ends of said beam being integrally provided with upwardly projecting legs respectively overlappingly secured to the outer sides of the hoppers, each of said legs being formed with a portion constituting a mounting for a door supporting mechanism.
9. In a railway car, the combination with a pair of spaced hoppers, each of said hoppers having a lading discharge opening and provided with a slope sheet and inner and outer side sheets, of doors for respectively closing the discharge openings of the hoppers, each of said hoppers being provided with door seat portions bordering the sides of its discharge opening, and a combined tie and reinforcing member for the hoppers comprising a beam extending beneath and rigidly secured to the slope sheet of each hopper, said beam having upwardly projecting legs respectively secured to the side sheets of the hoppers in overlapping relation to their door seat portions.
10. In a railway car, the combination with

- a pair of spaced hoppers, each of said hoppers having a lading discharge opening and provided with a slope sheet and inner and outer side sheets, of doors for respectively closing
- 5 the discharge openings of the hoppers, each of said doors being provided with outwardly projecting marginal flanges, the side sheets of each hopper being provided with portions adapted to be disposed in overlapping relation to the flanges of the associated door to form a seal against the escape of fine lading, and a combined tie and reinforcing member for the hoppers comprising a beam extending beneath and rigidly secured to the slope
- 10 sheets of the hoppers, said beam being integrally provided with upwardly extending legs respectively secured to the side sheets of the hoppers in overlapping relation to the flanges thereof.
- 15 11. In a railway car, the combination with a hopper having a lading discharge opening and provided with a slope sheet and inner and outer side sheets, of a door for closing the opening, said hopper being provided with
- 20 door seat portions bordering the sides of the opening, and a reinforcing member for the lower portion of the hopper, said member having upwardly extending legs rigidly secured to the side sheets in overlapping relation to the said door seat portions.
- 25 12. In a railway car, the combination with a hopper having a lading discharge opening and provided with a slope sheet and inner and outer side sheets, of a door for closing the opening having outwardly projecting marginal flanges, the side sheets of the hopper being provided with flanges adapted to be disposed in overlapping relation with the flanges of the door to form a seal against
- 30 the escape of fine lading, and a reinforcing member for the lower portion of the hopper, said member having upwardly extending legs rigidly secured to the side sheets in overlapping relation to the said flanges thereof.
- 35 13. In a railway car, the combination with a hopper having a lading discharge opening and provided with a slope sheet and inner and outer side sheets, of a door for closing the opening having outwardly projecting marginal flanges, the side sheets of the hopper being provided with door seat portions and with outwardly projecting flanges adapted to be disposed in overlapping relation with the flanges of the door to form a seal against
- 40 the escape of fine lading, and a reinforcing member for the lower portion of the hopper, said member having upwardly projecting legs rigidly secured to the side sheets in overlapping relation to their door seat portions.
- 45 14. In a railway car, the combination with a hopper having a lading discharge opening and provided with a slope sheet and inner and outer side sheets, of a hinged door for closing the opening, said door being provided
- 50 with outwardly projecting flanges along its side and free edges, the side sheets of the hopper being provided with flanges adapted to be disposed in overlapping relation with the side flanges of the door to form a seal against the escape of fine lading, and a reinforcing member for the lower portion of the hopper, said member having a portion secured to the underside of the slope sheet and upwardly projecting legs secured to the side sheet in overlapping relation to their flanges, the portion of the member secured to the slope sheet being formed with an outwardly projecting flange adapted to overlap the marginal flange along the free edge of the door.
- 55 15. In a railway car, the combination with a hopper having a lading discharge opening and provided with a slope sheet and inner and outer side sheets, and a reinforcing member for the lower portion of the hopper, said member having upwardly extending legs secured to the side sheets and an intermediate connecting portion secured to the slope sheet, said intermediate portion and said legs being integrally provided along their inner edges with a stiffening flange.
- 60 16. In a railway car, the combination with a hopper having a lading discharge opening provided with a slope sheet and inner and outer side sheets, of a door for closing the opening, and a reinforcing member for the lower portion of the hopper, said member having upwardly extending legs secured to the side sheets and an intermediate connecting portion secured to the slope sheet, the leg secured to the outer side sheet being integrally formed with a portion constituting a mounting for a door supporting mechanism.
- 65 17. In a railway car, the combination with a hopper having a lading discharge opening provided with a slope sheet and inner and outer side sheets, of a door for closing the opening, and a reinforcing member for the lower portion of the hopper, said member having upwardly extending legs secured to the side sheets and an intermediate connecting portion secured to the slope sheet, the leg secured to the outer side sheet being integrally formed with a portion constituting a mounting for a door supporting mechanism, and said intermediate portion being integrally provided with a stiffening flange, said flange extending upwardly along the inner edge of the leg secured to the outer side sheet and merging with the said mounting for the door supporting mechanism.
- 70 18. In testimony whereof I affix my signature.
- 75 WILLIAM E. WINE.
